UNITED STATES PATENT OFFICE.

WALTER FENTON, OF MANCHESTER, ENGLAND, ASSIGNOR TO UNDERWOOD TYPE-WRITER COMPANY, OF NEW YORK, N. Y., A CORPORATION OF DELAWARE.

TYPE-WRITING MACHINE.

1,309,322.

Specification of Letters Patent.

Patented July 8, 1919.

Application filed September 19, 1917. Serial No. 192,051.

To all whom it may concern:

Be it known that I, WALTER FENTON, a subject of the King of Great Britain, residing at 2 Adria road, Didsbury, Manchester, in the county of Lancaster, England, have invented new and useful Improvements in Type-Writing Machines, of which the following is a specification.

My invention relates to improvements in type writing machines and consists essentially of an improved carriage or paper support designed primarily to give the following variety of copies, simultaneously with the original typing of a letter, document or other matter, and without removing either the original or copy from the machine except in cases of substitution, as under the fourth head, when a fresh original would have to be inserted:

- 20 1. A copy of the whole or of a selected part or parts of the original.
2. Such copy in similar, condensed or extended spacing as compared with the original.
- 25 3. Such copy in similar, reverse or varied order as compared with the original.
4. A summary or list on one sheet of the essential or selected particulars of numerous originals and in any order.

30 5. Duplicates of the original or copy or both can be obtained in all cases.

My improved carriage may be applied to any suitable type of existing type writer nearly all the ordinary parts being retained as usually made except the platen roller, which is herein shown as of reduced diameter for compactness.

I illustrate my improved carriage in the accompanying sheet of diagrammatic drawings in which:—

Figure 1 is a front elevation of my improved carriage.

Figs. 2 and 3 are cross sectional elevations showing the platen bar and second carrier in two different positions.

Figs. 4 and 5 and 6 are views of details.

Fig. 7 shows another method of driving the small platen roller B.

The improved paper-carriage or support 50 consists of two work-sheet carriers, of which No. 1 comprises two sheet-guiding rollers D and E supported parallel to each other between and at right angles to two brackets

F fixed on or forming part of a main frame or carriage connected to or controlled by 55 the usual escapement mechanism of the machine. The roller D is preferably hollow and its pivotal extremities pass through and extend beyond the brackets F so that milled disks X or knobs or gearing for rotating the same may be secured thereon. The roller E (which might be termed a guide bar for the sheet) may be solid and its pivotal extremities are journaled in the brackets F, consequently both rollers D and 60 E are capable of separate rotary motion for controlling the position and line-feeding movement of the main sheet a, and the roller E may be furnished with a milled disk 10 at one or both ends to facilitate its rotation. 70 This sheet carrier No. 1 is so arranged that the most forward part of the roller D is vertically above, and the most forward part of the roller E is vertically under, the typing point of the machine. Carrier No. 2 75 for the work-sheet which is to receive the carbon impressions, comprises preferably two rollers A and B placed parallel to each other, and to the rollers D and E, and connected to each other by an endless band Y 80 extending practically the full length of the rollers A and B. The endless band Y might be dispensed with and the impression roller or platen B driven merely by the frictional contact of the moving paper or 85 other copy sheet b from the roller A, contact being maintained by pressure rollers 11 in the usual way, Fig. 7. The carrier No. 2 also comprises a metal platen bar C 90 preferably faced with rubber or other suitable material, and two elevating and depressing levers G for raising and lowering the front roller B and the platen bar C into or from the printing positions indicated in Figs. 2 and 3 respectively. The roller A is pref- 95 erably hollow and its pivotal extremities pass through and extend beyond the brackets F so that milled disks X' or knobs or gearing for rotating the same may be secured thereon, for feeding the work-sheet b. Each sheet 100 may thus be fed independently of the other.

On these pivotal extremities of the roller A beyond the brackets F are fulcrumed the two elevating and depressing levers G which project forward and support the ends of the 105 roller B and platen bar C, the latter being

placed above the roller B, and the parts C and G forming a frame hinged to the main frame or carriage brackets F. The parts of this sheet carrier No. 2 are so arranged that the roller A can be rotated by means of the milled heads X' or equivalents, and this rotary motion is communicated by means of the endless band Y to the revoluble platen or roller B, and the roller B and the platen bar C can be raised or lowered as required into the two positions shown in Figs. 2 and 3 by the elevation or depression of the levers G, so as to bring the impression point on the roller B or the platen bar C immediately behind the typing point of the machine.

In operation a sheet of paper, a to receive the inked type impressions and become the "original", is placed in the carrier No. 1 by passing it forward under the roller E then upward in a vertical plane and backward over the roller D, tension springs or clips or any suitable known device 12 being employed to guide and keep the paper a stretched between the rollers D and E as shown in Figs. 2 and 3.

A second sheet of paper b to receive the carbon impressions of the types and become the "copy", together with a sheet of carbon paper superimposed upon it in the well known manner, is placed in the carrier No. 2 by passing it forward under the roller A, up around the impression roller or platen B and backward over the roller A so that the copy sheet b is in contact with the outer side of the endless band Y and is stretched and maintained in position by any suitable tensioning device.

Alternatively, the carbon paper may be placed behind and run with the original on the rollers of No. 1 carrier.

To type the original sheet and at the same time to obtain a carbon impression on the copy sheet it is necessary to elevate the roller B and the platen bar C which causes the original sheet and the copy sheet with the carbon paper inserted between them to be presented in successive contact at and immediately behind the typing point of the type writer so that on the type keys being struck the types 13 will imprint characters on the original sheet a and produce carbon impressions on the copy sheet b.

To type on the original sheet a without giving a carbon impression on the copy sheet b it is necessary by means of the levers G to depress the roller B and the platen bar C, which causes the carbon sheet and copy sheet b to be removed from contact with the original sheet a and the platen bar C to be brought into contact with the original sheet a immediately behind the typing point of the type writer. The platen bar C then provides the necessary solidity behind the original sheet a so that on a type key being struck the platen bar C will enable a

character to be impressed on the original sheet a but will prevent any impression on the copy sheet b.

To obtain similar, condensed or extended spacing on the copy as compared with original:

a. *Similar spacing.*—Rotate the rollers A and D in the same direction and to the same extent.

b. *Condensed spacing.*—Rotate the roller A in the same direction as but a less distance than the roller D.

c. *Extended spacing.*—Rotate the roller A in the same direction as but a greater distance than the roller D.

To obtain similar, reverse or varied order on the copy as compared with the original:

a. *Similar order, (forward).*—Rotate the rollers A and B in the forward direction.

Similar order, (backward).—Rotate the rollers A and E in the backward direction.

b. *Reverse order.*—Rotate the roller A forward and E backward or rotate A backward and D forward.

c. *Varied order.*—Vary the direction with or without varying the distance of rotation of the roller A on the one hand and either D or E as required on the other.

To obtain on one copy sheet a summary of particulars extracted from numerous originals, it is necessary to retain the copy sheet in the carrier No. 2 while the various originals are passed through the sheet carrier No. 1, elevating the roller B and the platen bar C only during the periods in which the selected particulars are being typed on each original.

To obtain duplicate of either the original or copy it is necessary to insert in the particular carrier and behind the original sheet or copy sheet an additional sheet of paper on which is superimposed a carbon sheet in the manner commonly employed at present.

It will be readily understood that the details may be varied or modified without departing from the essential characteristic feature of the invention which consists in the construction and application of an improved carriage consisting of two carriers co-acting to enable the impression of the type to be varied as hereinbefore stated.

What I claim and desire to secure by Letters Patent of the United States is:—

1. In a type writing machine, the combination of two sheet-controlling or guiding rollers, an impression roller, a platen bar, means for rotating the impression roller, and means for moving the impression roller and the platen bar into and out of the typing position.

2. In a type writing machine, the combination of two sheet-carriers, of which one carrier comprises two rollers for controlling the original sheet, and the second carrier com-

prises a single impression roller and a platen bar, means for rotating the impression roller, and means for moving the impression roller and the platen bar into and out of the typing position.

3. In a typewriting machine, the combination with means for feeding and guiding a sheet, of a plurality of platens, each movable into and out of printing position relatively to said sheet.

4. In a typewriting machine, the combination with means for feeding and guiding a sheet, of a plurality of platens, and means for moving either platen into printing position relatively to said sheet and simultaneously moving the other platen out of such position.

5. In a typewriting machine, the combination with guides or feeders between which a work-sheet extends, of a plurality of platens mounted between said guides and feeders and movable into and out of printing position relatively to said sheet.

6. In a typewriting machine, the combination with guides or feeders between which a work-sheet extends, of a plurality of platens mounted between said guides and feeders, and a carrier whereon said platens are mounted, and whereby either platen may be carried into printing position and the other out of printing position relatively to said sheet.

7. In a typewriting machine, the combination with guides or feeders between which a work-sheet extends, of a plurality of platens mounted between said guides and feeders, and a carrier whereon said platens are mounted, and whereby either platen may be carried into printing position and the other out of printing position relatively to said sheet, one of said platens mounted for revolution.

8. In a typewriting machine, the combination with guides or feeders between which a work-sheet extends, of a plurality of platens mounted between said guides and feeders, and a carrier whereon said platens are mounted, and whereby either platen may be carried into printing position and the other out of printing position relatively to said sheet, one of said platens mounted for revolution and the other of said platens being non-revolvable and extending along the revoluble platen and close thereto.

9. In a typewriting machine, the combination with a plurality of platens, of means independent of said platens for guiding and feeding a work-sheet; each of said platens

movable into and out of printing position relatively to said sheet.

10. In a typewriting machine, the combination with types and a plurality of platens, of means independent of said platens for guiding and feeding a work-sheet, and means for enabling the types to coöperate with either platen in typing said work-sheet.

11. In a typewriting machine, the combination with types and a plurality of platens, of means independent of said platens for guiding and feeding a work-sheet, and means for enabling the types to coöperate with either platen in typing said work-sheet, one of said platens provided with means for carrying and feeding a work-sheet independently of the first work-sheet.

12. The combination of a main frame, a second frame movably mounted thereon; a plurality of platens carried by said movable frame for movement into and out of printing position, and means upon the main frame for guiding and feeding a work-sheet for coöperation with either platen.

13. The combination with a plurality of relatively movable frames connected together, of a plurality of platens carried by one of said frames, and means carried by the other of said frames for guiding and feeding a work-sheet for coöperation with either of said platens.

14. The combination of a revoluble platen and a fixed or non-rotating platen closely placed one above the other, and upper and lower sheet-feeding or guiding means between which said platens are mounted; said platens movable relatively to said sheet-feeding means, to bring either platen to printing position.

15. The combination of a revoluble platen and a fixed or non-rotating platen closely placed one above the other, upper and lower sheet-feeding or guiding means between which said platens are mounted; said platens movable relatively to said sheet-feeding means, to bring either platen to printing position, and a drive roller over which a work-sheet runs in rear of said revoluble platen, means being provided for operating said revoluble platen by means of said drive roller.

In testimony whereof I have signed my name to this specification in the presence of two subscribing witnesses.

WALTER FENTON.
